SKI SLED

Marc A. Brousseau, 7443 Frederick St., Detroit, Mich.

Filed Apr. 18, 1960, Ser. No. 60,234

Term of patent 14 years

(Cl. D34—15)

FIG.1.

FIG.2.

FIG.3.

Fig. 1 is a perspective view of a ski sled, showing my new design;

Fig. 2 is a side elevational view of the ski sled shown in Fig. 1; and

Fig. 3 is the top plan view of the ski sled.

I claim:

The ornamental design for a ski sled, substantially as shown.
